UNITED STATES PATENT OFFICE.

SAMUEL W. WILSON, OF ATWATER, OHIO.

SAFETY-LOCK FOR POCKET-BOOKS.

1,030,957.

Specification of Letters Patent.

Patented July 2, 1912.

Application filed February 9, 1912. Serial No. 676,566.

To all whom it may concern:

Be it known that I, SAMUEL W. WILSON, a citizen of the United States, residing at Atwater, in the county of Portage and State of Ohio, have invented a new and useful Safety-Lock for Pocket-Books; and I do hereby declare the following to be a full, clear, and exact description of the invention, such as will enable others skilled in the art to which it appertains to make and use the same.

This invention relates to a new and useful safety attachment for pocket books.

The invention aims to improve and simplify the structure of such attachments, particularly those illustrated, set forth and claimed in the Patents Nos. 921,775, granted May 18, 1909, and 1,004,127 granted Sept. 26, 1911, and to permit the pocketbook to be securely locked in the pocket by a single prong, adapted to be operated by only one operating member, for throwing the prong in and out of locking engagement with the pocket, thus effectively preventing an unauthorized withdrawal of the pocketbook or accidental falling of the same from the pocket.

Another object of the invention is the provision of means for locking the operating member in such a position as to prevent the same from being accidentally manipulated.

The invention comprises further features and combination of parts, as hereinafter set forth, shown in the drawings and claimed.

In the drawings: Figure 1 is a plan view of a foldable pocket book, showing the same equipped with the improved safety attachment. Fig. 2 is a plan view of a fragmentary portion of the pocket book, with the safety attachment applied, showing the locking prong projected. Fig. 3 is a sectional view on line 3-3 of Fig. 1. Fig. 4 is a sectional view on line 4-4 of Fig. 1. Fig. 5 is a detail perspective view of the locking mechanism, the portion 10 being bent outward so as to clearly disclose the structure in detail.

Referring to the drawings 1 designates the usual foldable pocket book, while 2 designates the base plate of the safety attachment. This base plate is constructed of sheet metal or the like, and is provided with suitable apertures 5 at each end, whereby the same may be attached to the pocket book by several strands of thread or the like 3. This base plate may be attached by rivets, if

deemed desirable and more efficient. A lever 6, pivoted at 7 at the lower end of the base plate, is provided with a prong 8 which is adapted to pierce the fabric of the pocket. 60 This prong is semi-circular, and engages a keeper 9, at one corner of the lower end of the base plate, when pierced through the fabric. This keeper 9 prevents the shield 10 from being pressed against the lever 6 65 with its prong. Integral with the base plate are a plurality of guides 11, 12, 13 and 14. These guides are stamped from the same metal from which the plate is formed. Mounted in the guides is a reciprocatory 70 connecting link 15, the end 16 of which is pivoted to the lever 6, as at 17, while the other end is pivoted at 18 to the operating lever 19. This operating lever is movable 75 in a pair of guides 20 and 21, and is formed with a lug 22.

When the lever 19 is disposed as shown in Fig. 1, that portion of the lever below the handle is arranged in engagement with any one of the teeth 23 of the guide 21, for holding the lug on the operating lever out of registration with the struck-up portion 24 of the guide 20. To throw the operating lever in the position as shown in Fig. 2, the same is moved until the lug is in registration with the depression, then the operating lever is depressed downwardly, moving the connecting link with it, against the action of the spring 25, thus feeding the lug through the depression. The spring 25 is connected between a tongue 26, which is struck up from the link 15, and a guide 12. Immediately 80 subsequently to depressing the operating lever, the same is moved laterally upon its pivot with the link 15, so as to cause the lug 90 22 to engage any one of the notches 27 of the guide 20, thus holding the prong 8 pierced through the fabric of the pocket and in engagement with its keeper 9. When the prong 8 is thrown to an unlocked position, 100 the lever 6 is limited in its movement by contacting with the projection 28, as shown.

The invention having been set forth, what is claimed as new and useful is:-

1. In combination, a foldable pocketbook, a base plate secured to one of the folding flaps of the pocket book, a lever having a piercing prong and pivoted at the lower end of the base plate, a link pivoted to the lever at one end, the base plate having guides for the link, an operating lever pivoted at one end to the upper end of the link, the base

- plate having guides for the operating lever, the lever having a lug normally arranged between the guides for the operating lever, one of the guides for the operating lever 5 having means to permit the lug to pass the guide when the operating lever is depressed, the guide having said means having means to be engaged by the lug to hold the lever depressed, while the other guide for the operating lever having teeth to hold the operating lever against being moved, and a spring connecting between the link and one of the guides of the base plate for holding the moving parts in their normal positions.
- 15 2. In combination, a foldable pocketbook, a base plate secured to one of the folding flaps a lever having a piercing prong and pivoted at the lower end of the base plate, a link pivoted at its lower end to the lever and 20 guided adjacent the base plate, an operating lever having a lug and pivoted at one end to the upper end of the link, a pair of guides for the operating lever between which the

lug thereof is normally arranged, one of the guides having a transverse struck-up portion 25 to permit the lug to pass the guide, when the operating lever is depressed, the guide having the struck-up portion having notches to be engaged by the lug to hold the lever depressed, while the other guide is provided with teeth to hold the operating lever against being manipulated, a spring connecting between the link and a part of the base plate for holding the moving members in their normal positions, the base plate having 30 a keeper for the extremity of the prong, and means on the base plate to limit the lever with the prong in its normal position.

In testimony whereof I have signed my name to this specification in the presence of 40 two subscribing witnesses.

SAMUEL W. WILSON.
